T. H. SEELY.
WAX THREAD SHOE SEWING MACHINE.
APPLICATION FILED NOV. 27, 1916.

1,253,635.

Patented Jan. 15, 1918.

UNITED STATES PATENT OFFICE.

THOMAS H. SEELY, OF BOSTON, MASSACHUSETTS, ASSIGNOR, BY MEANS ASSIGNMENTS,
TO UNITED SHOE MACHINERY CORPORATION, OF PATERSON, NEW JERSEY, A COR-
PORATION OF NEW JERSEY.

WAX-THREAD SHOE-SEWING MACHINE.

1,253,635.

Specification of Letters Patent. Patented Jan. 15, 1918.

Original Application filed January 29, 1914, Serial No. 815,127. Divided and this application filed November 27, 1916. Serial No. 133,620.

To all whom it may concern:

Be it known that I, THOMAS H. SEELY, a citizen of the United States, residing at Dorchester, Boston, in the county of Suffolk and State of Massachusetts, have invented certain new and useful Improvements in Wax-Thread Shoe-Sewing Machines; and I do hereby declare the following to be a full, clear, and exact description of the invention, such as will enable others skilled in the art to which it appertains to make and use the same.

This invention relates to wax thread shoe sewing machines employing a curved hook 15 needle and a looper.

In wax thread sewing machines it is desirable that the thread be kept hot right up to the sewing point, in order that the wax which has been applied to the thread may 20 be in the proper condition at the time that the thread is incorporated into the seam.

The object of the invention is to provide shoe sewing machines with heating devices for transmitting heat to the looper which 25 will enable the looper to be heated to a greater degree and maintained at a more nearly uniform temperature than in machines heretofore devised.

With the above object in view, the invention comprises the novel and improved features of construction, arrangements and combinations of parts set forth in the following description and pointed out in the claims, the advantages of which will be 35 obvious to one skilled in the art.

The present application is a division of an application, Serial No. 815,127, filed January 29, 1914.

In the drawings illustrating a shoe sewing machine embodying the invention in its preferred form, Figure 1 is a view in side elevation of the forward portion of the head of the machine, and Fig. 2 is a detail sectional view taken substantially on the line 45 2-2 of Fig. 1.

The machine illustrated in the drawings is a shoe sewing machine of the class employing a curved hook needle and devices co-operating therewith to form a chain 50 stitch seam, and is particularly designed for sewing welts and uppers to the insoles of welted shoes, although with slight changes it may be used in sewing uppers to the soles

of turned shoes. The curved hook needle indicated at 2, the needle guide 4, the thread finger 6, and the channel guide 8, are all constructed and arranged in the same manner, and are operated by the same mechanism as the corresponding parts of the machine illustrated in the patent to Andrew Eppler No. 1,108,560 dated August 25, 1914.

The looper of the machine illustrated in the drawings is actuated in substantially the same manner as the looper of the machine illustrated in the above Eppler patent. In order to enable the looper to be heated more efficiently than in prior machines, certain improvements have been made in the mechanism for supporting and actuating the looper. The looper indicated at 10 is secured by a clamping screw 12 in a socket in the lower end of an arm 14 pivoted intermediate its ends to oscillate in a plane substantially perpendicular to the plane of the needle upon the forward end of a slide 16, which slide is arranged to reciprocate in a direction substantially parallel with the plane of the needle. The upper end of the arm 14 is provided with a socket or bore to receive a stud projecting from a sleeve 18, which forms a bearing to receive a rod 20 secured to the outer end of an arm 22 carried by a rock shaft 24. A second arm 26 is secured to the rock shaft 24, and carries a cam roll which engages a cam groove in a cam disk mounted on the main shaft of the machine. Through the connections described the movements of the rock shaft 24 impart oscillating movements to the arm 14. Forward and rearward movements are imparted to the looper by the reciprocation of the slide 16, and the oscillation of the arm 14 swings the looper in a plane substantially perpendicular to the plane of the needle, the movements of the slide and the arm being relatively timed to carry the looper about the needle. A block 28 is secured to the forward end of the slide 16, and embraces the arm 14, as illustrated in Fig. 2. The arm 14 is supported on the slide by means of a hollow shaft 30 passing through suitable bearings in the arms of the block 28 and in the central portion of the arm 14. The bore in the shaft 30 does not extend completely through the rear end of the said shaft, and the forward end of the bore

is closed by a plug 32 screwed into the end of the shaft. The chamber thus formed is connected by a coupling 34 with a pipe 36 which leads from a steam chamber in a plate 38 forming a part of the frame of the head of the machine. The steam is conducted from the generator to the chamber in the plate 38 by means of an inlet pipe 40, a passage 42 through the frame and a pipe 44 connecting the passage with the chamber in plate 38. The steam is led from the chamber in the shaft 30 by means of an outlet pipe 46 connected at its forward end with said chamber. To hold the hollow shaft 30 securely from longitudinal movement, a bracket 48 is secured to the plate 38, and is provided with a downwardly extending arm which engages a groove in the coupling 34. By providing a steam chamber in the shaft 30 upon which the looper carrying arm is pivoted, this arm and the looper itself are heated in an efficient manner so that the waxed thread as it passes from the looper eye is in a proper condition for forming a satisfactory tight seam.

Having explained the nature and object of the invention and having specifically described a machine embodying the invention in its preferred form what is claimed is:—

30 1. A shoe sewing machine, having, in combination, stitch forming devices including a curved hook needle, a looper, means for supporting and actuating the looper to lay the thread in the hook of the needle comprising a slide mounted to reciprocate in a direction parallel with the plane of the needle, a hollow shaft arranged parallel with the slide and supported thereby, a looper carrying arm pivoted on said shaft and connected to

35 40 reciprocate with the slide, and devices for heating the hollow shaft.

2. A shoe sewing machine, having, in com-

bination, stitch forming devices including a curved hook needle, a looper, means for supporting and actuating the looper to lay the thread in the hook of the needle comprising a slide mounted to reciprocate in a direction parallel with the plane of the needle, a longitudinally fixed hollow shaft arranged parallel with the slide and supported thereby, a looper carrying arm pivoted on said shaft and connected to reciprocate with the slide, and devices for heating the hollow shaft.

3. A wax thread sewing machine, having in combination, stitch-forming devices including a curved hook needle, a looper, a looper actuating slide, looper supporting devices mounted on the forward end of the slide to reciprocate therewith, and comprising a pivoted looper lever and a looper heater fixed in the direction of movement of the slide and having a continuous heat conducting contact with one of the looper supporting devices.

4. A wax thread sewing machine, having in combination, stitch-forming devices including a curved hook needle, a looper, a looper actuating slide, a looper lever pivotally supported on the forward end of the slide to reciprocate therewith, and a fixed looper heater having a continuous heat conducting contact with the hub of the looper lever.

5. A wax thread sewing machine, having, in combination, stitch forming devices including a curved hook needle, a looper, a looper lever, a hollow shaft upon which the looper lever is mounted, a slide for reciprocating the lever on the shaft, a rock shaft for oscillating the lever and devices for heating the hollow shaft.

THOMAS H. SEELY.
